M. MIZRAHI

BOAT TOP

Filed March 20, 1924

UNITED STATES PATENT OFFICE.

MOZ MIZRAHI, OF NEW YORK, N. Y.

BOAT TOP.

Application filed March 20, 1924. Serial No. 700,458.

To all whom it may concern:

Be it known that I, MOZ MIZRAHI, a citizen of Greece, residing at New York city, borough of Manhattan, in the county of 5 New York and State of New York, have invented certain new and useful Improvements in Boat Tops, of which the following is a specification.

This invention relates to new and useful 10 improvements in storm canopies or awnings comprising sun shades, intended principally for the protection and comfort of the occupants of a pleasure or other boat.

This invention provides a new and unique 15 construction for a canopy, being one which is at once rugged, simple to operate and cheap to manufacture.

Another object of my invention is to provide a canopy the form of which is in harmony 20 with the lines of the boat so that the appearance of the boat when the canopy is in use is thereby considerably improved.

Another object of my invention is to provide a canopy which from an operating 25 standpoint is exceedingly flexible in that it may be positioned in a variety of ways with equal facility, with the particular result that when the canopy is not in use it may be securely held in position at either side of the 30 boat without inconvenience to the occupants thereof if they should desire to use the oars, and without obstructing their view.

Another object of my invention is to provide a canopy having a sun shade manipulatable for a variety of positions so as to suit 35 the convenience of the occupants of the boat.

Still another object of my invention is to provide a canopy comprising a sun shade in 40 which the fasteners are simple in construction and so arranged that comparatively few of them will suffice to retain both the sun shade and the main portion of the canopy in such different positions as the occupants of the boat may desire.

With the foregoing and other objects in view the invention consists in the arrangement and combination of parts hereinafter described and claimed, and while the invention is not restricted to the exact details of 45 construction disclosed or suggested herein, still for the purpose of illustrating a practical embodiment thereof reference is had to the accompanying drawings, in which like reference characters, designate the same parts in the several views, and in which—

Figure 1 is a side view of the boat showing my canopy and sun shade in use.

Fig. 2 is a section along the line 2—2 of Fig. 1.

Fig. 3 is a central cross-section of the 60 boat showing the storm canopy in use, while the sun shade is folded away.

Fig. 4 is a central section of the boat showing the canopy folded and put away at the 65 side of the boat.

Fig. 5 is a detail of the end portions of the canopy bows showing their manner of attachment to the boat.

Fig. 6 is an enlarged detail view of the 70 canopy as shown in Fig. 4.

The boat 10 has a seat 11 and a railing 12. This railing bears at its fore and aft ends the U forks 13 which are fitted with the pivots 14. The bows 15 and 16 are made of flat metal strips and are pivoted upon the 75 pivots 14. Their symmetrical construction as shown by the shape of the canopy in the side view is noteworthy. The main portion of the awning or canopy 17 consisting of a heavy watertight fabric is secured to these 80 bows, the side bows 16 bearing in addition the drop curtains 18 secured thereto. These curtains are made preferably of a light fabric and may be more or less ornamental in appearance. The bows 16 are offset as at 19 85 to allow a clearance between the bows for the curtains 17 when the canopy is folded away as shown in Fig. 4. The canopy 17 and the curtains 18 are fastened to the bows by any suitable means such as hollow rivets 90 flattened over.

Guy members such as springs 20 are permanently secured to the bows 16 at 21. The hook and eye connection 25 serves to fasten the free end of the spring to the railing, so 95 that the canopy is held in rigid elevated and open position without allowing any folds or wrinkles to appear in the canopy since the springs cause a lateral tension thereon. These springs are so located as not to interfere 100 with the manipulation of the oars by the rower.

The shades or curtains 18 may then be secured in position by means of the straps 22 fastened hereto, which are adapted to engage 105 with the buttons 23 secured to the side of the boat. The edges of the curtains will then be sufficiently low to substantially meet the railing, so that the interior of the boat may in this way be made substantially tight against 110

wind and rain, besides serving the purpose when occasion arises as has already been indicated, of acting as sun shades. The flexibility of the canopy due to the spring construction allows the curtains to be easily fastened or unfastened when operator thrusts his hand into the space between the curtain and the railing. While there are four curtains any number of these, in any combination, may be used at once, depending upon the position of the sun or the direction of the wind. Thus only one of the four might be used, or then again two might be used upon the one side or the other, the front or the rear of the boat.

When it is desired to use the main portion of the canopy alone, the sun shades may be folded upon themselves as shown in Fig. 3, so as to hug the under portion of the awning, and may be fastened thereto by means of the buttons 24, using the very same straps 22 which were used to secure the curtain to the buttons 23. The economy of this construction is manifest.

When the canopy is folded away it is swung to a side of the boat, being thus out of the way. An unobstructed view is then open to the occupants of the boat, who may use oars if they so desire. The spring 20 is then passed around the canopy and the hook and eye connection 25 locked, thus helping to support and rigidly hold said canopy.

The superiority of my construction will be noted also in that the form of the bows is curved, and this, together with their arrangement allows the use of a canopy of very simple cut, no extensive fabrication or preparation being necessary before it is fastened to the bows. Another advantage is that while the central portion of the canopy is sufficiently high to permit of reasonable head room, the ends of the canopy are substantially at the level of the railing of the boat. Any end coverings which appear to

be indispensable in the prior art if the end portions of the boat are to be protected against wind and rain, are thus rendered unnecessary.

I claim:

1. In a canopy adapted for use on a boat, the combination with a plurality of side bows pivoted at the ends of the boat and adapted to swing transversely thereof, of a cover supported by the bows and fastened thereto so as to limit the swing of the side bows relatively to each other, one of said side bows being adapted to lie in spaced relation to one gunwale while the other side bow lies in spaced relation to the other gunwale, and tension means secured at the sides of the boat adapted to engage said side bows to draw them with equal force toward the gunwales, thereby causing a tension in said cover and thus securing the bows in spaced relation with each other and with the gunwales and the canopy in unfolded upraised position.

2. The combination as in claim 1 wherein a curtain is fastened to one of said side bows adapted to substantially span the space between the gunwale and its supporting bow and to lie against the under side of said cover.

3. The combination as in claim 1 wherein a curtain is fastened to one of said side bows adapted to substantially span the space between the gunwale and the bow supporting said curtain and to lie within said tension means so that said curtain can be folded up to lie against the under side of said cover, said curtain comprising fastening means adapted both to secure the free edge of the curtain to the side of the boat when the curtain is opened up, and to the under side of the cover when folded away.

In testimony whereof I affix my signature.

MOZ MIZRAHI.
